UNITED STATES PATENT OFFICE.

JASPER N. DAVIS, OF DENVER, COLORADO.

FILLING PLUG FOR STORAGE-BATTERY COVERS.

Application filed April 20, 1925. Serial No. 24,427.

To all whom it may concern:

Be it known that I, JASPER N. DAVIS, a citizen of the United States of America, residing at the city and county of Denver and 5 State of Colorado, have invented a new and useful Filling Plug for Storage-Battery Covers, of which the following is a specification.

This invention relates to improvements in 10 filling plugs for the covers of storage battery jars.

The object of the invention is to provide an improved filling plug, which is adapted to replace the usual cap form of plug, and 15 which is provided with indicating means by which the level of the battery solution above the tops of the plates in the jar can be ascertained at all times, without the necessity of removing the plug.

20 Further to provide a filling plug having an upper portion provided with sight openings and depending guide members which extend down into the jar and inclose a float having an upwardly projecting stem which 25 is visible through said sight openings, the position of the upper end of said stem with respect to the lower edges of said sight openings, indicating the level of the battery solution above the tops of the plates in the jar.

30 These objects are accomplished by the device illustrated in the accompanying drawings in which:

Figure 1 is a vertical sectional view through the upper portion of a battery showing 35 the jar cover provided with the improved filling plug.

Figure 2 is an enlarged perspective view of the improved plug.

40 Figure 3 is a top view of the plug.

Figure 4 is a bottom view thereof.

Figure 5 is a top view of a portion of a jar cover embodying the improved indicating means and also provided with the usual filling hole adapted to be closed by the common form of cap or plug, and

45 Figure 6 is a sectional view on the line 6—6 of Figure 5, the filling hole being closed by a common form of plug.

50 Referring to the accompanying drawings: The numeral 1 indicates the usual wood case; 2, the rubber jar, and 3, the cover, which is of hard rubber and which is secured in the upper end of the jar by a sealing compound 4. The cover is provided with two 55 holes 5, through which the cell posts pass, and with a hole 6 in which is screwed, or

otherwise secured, the usual filling plug. The hole 6 is in the upper end of the usual filling tube through which water is added to replace evaporation in the jar and through 60 which hydrometer readings may be taken to ascertain the strength of the battery solution. In the present style of cover, no provision is made for ascertaining the level of the water in the jar, other than by removing 65 the plug and looking into the filling tube, and as this is often forgotten or neglected, especially by inexperienced persons, the continued evaporation of the water exposes the 70 tops of the plates, with the consequent injurious results. The present invention, however, is adapted to prevent such injury to the battery by providing a plug having an indicating element which at all times shows the exact level of the battery solution in the 75 jar.

The improved plug comprises a circular disk-like body portion 7, from the upper face of which extends a hollow conical head 8, through the wall of which are formed preferably three equi-distant vertically disposed sight openings 9. From the lower face of the body portion 7, extends a hub-like member 10, which may be threaded to the hole 6, or secured therein in any other suitable manner, and which terminates in two or more depending guide legs 11, the outer and inner faces of which are concentric with the axis of the plug. The threaded hub portion 10 is, in the present instance, screwed into the 80 filling hole 6, which is surrounded by a raised lip 12, and a rubber gasket or washer 13, is interposed between the lip 12 and the body 85 of the plug which bears against the said washer, as clearly shown in Figure 1. The 90 guide legs 11, extend down to within a slight distance of the tops of the plates, indicated by the line 14 in Figure 1, and the inner faces of the lower end portions of these legs are formed with horizontal grooves 15, and the ends of the legs are outwardly curved 95 from the under sides of the said grooves, as clearly shown in Figure 2.

The lower sides of the grooves 15 are of 100 less depth than the upper sides, or in other words, the upper sides of the grooves extend inward beyond the lower sides thereof, owing to the reduced thickness of the extremities of the legs.

110 A float 16 is placed within the legs 11, and this float preferably comprises a circular hollow glass body from which projects an

upright stem 17, which extends through an axial hole 18, in the body 7, of the plug, and into the hollow head 8, so that the upper portion of the stem can be seen through the 5 sight openings 9. The float is held within the guide legs by a resilient rubber disk 19, which is sprung into the grooves 15, as shown in Figure 1, the upper faces of the grooves which extend inward beyond the 10 lower faces hereof, acting to engage the disk 19, and prevent it from being pressed past the slots 15, when inserting the disk in the plug.

Water is poured into the jar through the 15 opening 6, until it reach the bottom of the cover 3, and the improved plug is then screwed into the said opening, and the water in the jar will raise the float, the upper end of which will be as far above the lower ends 20 of the sight openings, as the body of the float is above the disk 19, and as the water evaporates the float will drop, thus indicating the depth of water above the top of the plates.

25 In Figures 5 and 6, I have shown a modification of my device in which a cover 3^A is employed, which is formed with an integral hollow head 20, similar to the head 8, and which is provided with sight openings

30 21. A hole 22 is formed in the cover in axial line with the head 20, and integral guide legs 23, similar to the legs 11, depend from the bottom side of the cover, concentric with the hole 22, the lower ends of these 35 legs being provided with grooves 24, to receive a float retaining disk 25, similar to the disk 19, shown in Figure 1. A float 16 is placed within the legs 23, the stem 17, of which passes up through the hole 22, 40 and into the hollow head 20, as in Figures 1 and 2.

In addition, this form of cover 3^A, is also provided with a threaded filling hole 26, which is normally closed with an ordinary 45 threaded cap 27. By this arrangement, not only can the depth of the electrolyte be ascertained at all times by the float 16, but the screw cap can be removed either for adding water to replace evaporation in the jar 50 or for the insertion of a hydrometer syringe for testing the strength of the battery solution.

By the employment of either the removable filling plug having the float, in connection with the form of cover in common use, or the improved form of cover having the float and also the usual filling opening, I provide a simple and practical means for indicating at all times the level of the battery solution above the tops of the plates in the jar, and thereby eliminate the chance 60 of injury to the battery through neglect in

adding water to replace evaporation in the jar.

Having described my invention, what I 65 claim as new and desire to secure by Letters Patent is:

1. In battery construction, the combination with the jar cover having a detachable hollow projection provided with sight openings; of a float having a stem visible through said sight openings, a depending vertical guideway on said hollow projection for said float and a stop at the bottom of said guideway, the position of the upper end of said 70 stem with respect to the lower ends of said sight openings indicating the level of the battery solution above the tops of the plates.

2. The combination with a battery jar cover, a detachable hollow member thereon having sight openings therein, a depending guideway on said hollow member provided with an axial hole in the upper end thereof opening into said hollow member; of a float in said guideway having a stem which extends through said axial hole and into said 80 hollow member, and a removable stop in the bottom of said guideway, the position of the upper end of said stem with respect to the lower ends of said sight openings, indicating the level of the battery solution above the tops of the plates.

3. In battery construction, a battery jar cover having a filling opening therein and a cap therefor, an upwardly projecting hollow member having sight openings therein, a hole in said cover in line with the axis of said hollow member, guide legs depending from the under side of said cover and concentric with said hole, a float within said 90 guide legs having a stem which extends through said hole and into said hollow member; said guide legs having grooves in the lower end portions of their inner faces and a resilient rubber disk which is sprung into 95 said grooves to form a stop for said float, the position of the upper end of said stem with respect to the lower ends of said sight openings, indicating the level of the battery solution above the tops of the plates.

4. The combination with a jar cover having an opening; of a plug adapted to be secured in said openings, having an upwardly projecting hollow member provided with sight openings and depending guide legs concentric with the axis of said hollow member, a float within said guide legs having a stem which projects into said hollow member and visible through said sight openings, and a disk removably secured in the lower ends of said guide legs to hold said float therein.

In testimony whereof I affix my signature.
JASPER N. DAVIS.
